(57) **CLAIM**

The ornamental design for an electronic device, as shown and described.

DESCRIPTION

FIG. 1 is a top view of an electronic device according to one embodiment;

FIG. 2 is a bottom view of the electronic device from FIG. 1;

FIG. 3 is a side view of the electronic device from FIG. 1; FIG. 4 is an alternate side view of the electronic device from FIG. 1;

FIG. 5 is a front view of the electronic device from FIG. 1; FIG. 6 is a back view of the electronic device from FIG. 1; FIG. 7 is a perspective view of the electronic device from FIG. 1;

FIG. 8 is another perspective view of the electronic device from FIG. 1;

FIG. 9 is a side view of the closed electronic device from FIG. 1;

FIG. 10 is a perspective view of the closed electronic device from FIG. 1; and,

FIG. 11 is a perspective view of the electronic device from FIG. 1 showing the display separated from the base. Broken lines shown in the figures depict environment only, and form no part of the claimed design.
